UNITED STATES PATENT OFFICE.

EDWIN B. NATHAN, OF YONKERS, NEW YORK.

SEAT COVER.

Application filed November 15, 1923. Serial No. 674,816.

To all whom it may concern:

Be it known that EDWIN B. NATHAN, citizen of the United States, residing at Yonkers, in the county of Westchester and State of New York, has invented certain new and useful Improvements in Seat Covers, of which the following is a specification.

This invention relates to improvements in seat covers, and more particularly to that 10 class of seat covers which are removable, portable, and foldable, so that the device can be readily packed and stored and occupy but small space when not in use.

One object of the invention is to provide 15 a seat cover comprising a single integrally woven strip, such for example as straw matting which is folded across the warp and along the woof thereof and reinforced or strengthened at its edges along the warp and 20 across the woof between the fold lines, so that when in operation there is provided a back, seat, and apron or drop to conform to the shape of the seat on which it is used.

A further object is to provide a seat cover 25 of the character stated which is sufficiently flexible transversely to bend or curve with the weight or pressure of the body but which is strengthened longitudinally to prevent collapse thereof.

30 A further object is to provide a seat cover which can be manufactured at a reasonable low price, which can be kept clean and sanitary, which is comfortable to the user, and which has a high degree of strength and 35 durability as well as neatness and attractiveness in appearance.

Other objects of this invention will in part be obvious and in part hereinafter pointed out.

40 The invention accordingly consists in the features of construction, combinations of elements and arrangement of parts which will be exemplified in the construction hereinafter described, and of which the scope of application will be indicated in the following 45 claims.

In the accompanying drawings, in which is shown one of the various possible illustrative embodiments of this invention,

50 Fig. 1 is a perspective view showing my improved seat cover in operative position;

Fig. 2 is a top plan view of the cover when straight;

55 Fig. 3 is an enlarged view in section on line 3—3 of Fig. 2; and

Fig. 4 is a bottom plan view of the cover.

My improved seat cover is composed of a single strip A of flexible material, preferably straw matting, with the woof of the strip running transversely of the cover so that the strip A will readily fold on lines 1 and 2 to provide a back 3, seat 4, and depending apron or drop 5. Over the fold lines I preferably secure flexible tapes 6 which re-inforce the cover at these points and at the same time serve to give the cover a neat and finished appearance.

To prevent crumpling or collapse of the sections 3, 4 and 5, re-inforcing members such as flat pieces of steel or the like material are held under tapes 8 adjacent the longitudinal edges of the sections and extend transversely of the woof of the material, the ends of such re-inforcing members being spaced sufficiently from the fold lines 1 and 2 to permit free folding action. The tapes 8 are stitched along their edges as at 8^a, 8^b to the top of the cover or may be otherwise suitably secured thereto thus providing pockets or receptacles for these reinforcing strips.

For neatness and strength, a binding tape 9 is preferably provided along the marginal edges of the strip A. Wear sheets 10 may also be secured to the back of said strip A at its ends. The strip A is folded on the lines 1 and 2 either to take the shape shown in Fig. 1, when in use, or to fold the sections upon each other for storage or shipping.

When in operation, the nature of the material with its woof strands running transversely of the cover prevents collapse or crumpling, yet permits such transverse bending or curvature of the sections as to render the cover comfortable and make it conform to the shape of the body and seat. The reinforcing or strengthening strip 7 being preferably of resilient material, lends all necessary stiffness to the seat sections and at the same time allows the sections to bend or curve to conform to the body or seat on which the device is employed.

By constructing the device of a single strip of straw matting or the like, the sections readily fold along the woof strands and no separate hinge connections are necessary. This not only makes for economy in the cost of manufacture, but also results in a continuous seat cover without break or opening, less liable to accumulate dirt and dust at the folds.

It will thus be seen that there is provided

a device in which the several objects of this invention are achieved and which is well adapted to meet the conditions of practical use.

5 As various possible embodiments might be made of the above invention and as various changes might be made in the embodiment above set forth, it is to be understood that all matter herein set forth or shown in 10 the accompanying drawings is to be interpreted as illustrative and not in a limiting sense.

Having thus described my invention, I claim as new and desire to secure by Letters 15 Patent:-

1. A collapsible seat cover comprising a single strip of flexible material adapted to be folded into sections, and resilient reinforcing members extending longitudinally over said material and spaced longitudinally from each other so as to permit folding of the material transversely of said reinforcing members said material being yieldably stiff transversely of the length of 25 said strip.

2. A collapsible seat cover comprising a single strip of flexible material adapted to be folded into sections, and reinforcing members extending longitudinally over said 30 material and spaced longitudinally from each other so as to permit folding of the material transversely of said reinforcing members, and means for holding said members in position and concealing them from 35 view, said material being yieldably stiff transversely of the length of said strip.

3. A collapsible seat cover composed of a single strip of woven material adapted to be folded along the woof thereof to form a plurality of sections, and resilient strengthening strips secured across the woof of the 40 sections the structure of said material being yieldably stiff transversely of the length thereof.

4. A collapsible seat cover composed of a single strip of woven material adapted to be folded along the woof thereof to form a plurality of sections, and pairs of spaced resilient strengthening members secured across the woof of the material adjacent the edges 45 of the sections the structure of said material being yieldably stiff transversely of the length thereof.

5. A seat cover composed of a single strip of straw matting folded along the woof 50 thereof to form a plurality of sections, resilient strengthening members spaced longitudinally and disposed across the woof of the material adjacent the edges of the sections, and covering tapes secured to the sections and enclosing said strengthening strips the structure of said material being yieldably stiff transversely of the length thereof.

6. A seat cover composed of a single strip of straw matting folded along the woof 55 thereof to form a plurality of sections, flexible and pliable strengthening tapes secured over the fold lines, resilient strengthening strips located adjacent the edges of the sections and extending across the woof of the 60 material thereof, tapes covering the strengthening strips, and a binding tape around the edges of the material.

7. A seat cover composed of a single strip of straw matting folded along the woof 75 thereof forming a plurality of sections, strengthening tapes secured over the fold lines, resilient strengthening strips located adjacent the edges of the sections and extending across the woof of the material 80 thereof, tapes covering the strengthening strips, and a binding tape around the edges of the material, and wear sheets secured to the backs of the end sections.

In testimony whereof I affix my signature.

EDWIN B. NATHAN.
